UNITED STATES PATENT OFFICE.

JERRY T. DWYER, OF YOUNGSTOWN, OHIO.

GAME APPARATUS.

Application filed March 24, 1926. Serial No. 97,041.

My present invention pertains to a pitching or driving game apparatus; and it has for its general object the provision of an apparatus that is self-supporting, is compact and easily adjusted, and is designed when used in conjunction with a ball and a golf club to enable a golf player to increase his skill in pitching or driving the ball, as well as to play a scoring game in which a given number of points is counted for each perfected shot.

Another object of the invention is the provision of an apparatus for the general purposes indicated that is adapted to be quickly and easily set up, either indoors or outdoors, and maintained in working position without entailing attaching of any part of the apparatus to the floor, ceiling or other part of the room or hall, or to any support whatsoever, whether indoors or outdoors.

Another object is the provision of a pitching or driving apparatus susceptible of being folded and thereby reduced to a bundle of small compass for storage or shipment and also capable of being expeditiously and easily set up ready for use without the employment of skilled labor and without the assistance of any tools whatsoever.

My novel game apparatus is susceptible of use in any place whatsoever, such as golf clubs, schools, amusement parks and homes.

Other objects, advantages and uses of the invention will be fully understood from the following description and claims when the same are read in connection with the drawings, accompanying and forming part of this specification, in which—

Figure 1 is a front elevation showing the apparatus constituting the best practical embodiment of my invention that I have as yet devised.

Figure 2 is a longitudinal vertical central section of the apparatus.

Figure 3 is a view of a fragmentary detail hereinafter explicitly referred to.

Similar numerals of reference designate corresponding parts in all of the views of the drawings.

Among other elements my novel apparatus comprises a wall 1 which is preferably formed of canvas or other appropriate flexible material, though if deemed expedient it may be formed of material that is stiff. The said wall 1 is provided with four, more or

less, apertures 2, and, within the purview of my invention, the said apertures 2 may be variously shaped and arranged in the discretion of the manufacturer. As shown the apertures include upper and lower horizontally extending slots and vertically arranged and spaced slots located in a plane between the plane of the horizontal slots. My invention also contemplates providing the said apertures 2 with different numbers as illustrated, for scoring purposes, the score made by the pitching or driving of a golf ball through either of the two vertical slot-like apertures being higher than the scores made when the ball is driven through one of the horizontally disposed slot-like apertures.

To carry out the self-supporting feature, which is one of the basic principles of the apparatus, the wall 1 is arranged between and connected to upright frame members 3, and hingedly connected at 4 in appropriate manner to the upper end of the board 1 are prop members 5, the said prop members 5 being normally maintained in the position illustrated in Figures 2 and 3 through the medium of foot braces 6 which are hingedly connected at 7 to the uprights 3 and are designed at 8 to be detachably connected to the lower ends of the prop members 5; each of the connections 8 being preferably made up of a pin extending from the adjacent prop member 5 and through an aperture in the foot brace 6, and a wing nut mounted on and removable from the said threaded pin.

At 9 is a pocket designed to receive balls impelled through the apertures 2 and also designed to facilitate the passage of such balls to an opening 10 in the board 1 for the return of the balls or ball to the player. The said pocket 9 is formed by a wall 10* on the prop members 5, side walls 11 of flexible character interposed between and connected to the uprights 3 and the prop members 5 and an inclined bottom wall 12 the lower edge of which is coincident with the lower wall of the before mentioned opening 10. It will also be understood by comparison of Figures 1 and 2 that the bottom 12 is provided with sloping side portions 13 which decline to the central portion of the said bottom 12 for the purpose of assuring the prompt gravitation of a ball to the opening 10 and the passage of said ball forwardly through said opening 10. I prefer, in practice, to

provide the opening 10 with a flap 14, Figure 2, the said flap 14 being of flexible material and attached along its upper edge in appropriate manner to the wall 1 above the opening 10.

It will be apparent from the foregoing that a player standing at an appropriate distance in front of the wall 1 is enabled through the medium of a golf club to drive or pitch a ball through one of the apertures or openings 2, and inasmuch as considerable skill is necessary for the pitching or driving of a ball through any one of the apertures 2 it will be appreciated that the use of my apparatus will increase the skill of a golf player.

At 15, Figures 1 and 2, are extension rods arranged back of and in parallelism to the prop members 5. The said extension rods 15 are preferably, though not necessarily, knobbed at their upper ends as designated by 16 so as to avoid marring of a ceiling or the like. The said extension rods 15 are carried through guide eyes 17 on the prop members 5, and the upper of the said guide eyes 17 are provided with set screws 18 through the medium of which the rod extensions 15 may be adjustably fixed to the prop members 5, according to the height of the room in which the apparatus is to be located.

Approximately attached to and extending laterally and also forwardly from the uprights 3 and also from the extension rods 15 are wings 20 of netting, the said wings 20 being designed in conjunction with a supplemental top netting 21 carried by the extension rods 15, to lessen the pitching or driving of a ball at either side or above the wall 1. These wings 20 and top netting 21 are entirely detachable and may be used as an accessory, but are not essential to the apparatus proper. The wings 20 are preferably provided with marginal cables 22, Figures 1 and 2, and each of the said marginal cables 22 is equipped at its lower end with a weight 23, the said weights 23 having for their function to maintain the wings 20 in stretched state and against casual movement so as to better enable the wings to perform the function ascribed to the same.

Manifestly when it is desired to fold the apparatus and reduce the same to a small compass, the wings 20 may be folded or collapsed so as not to add materially to the bundle formed by the folded or collapsed apparatus. It will also be readily appreciated in this connection that when folded or collapsed, the apparatus is susceptible of being expeditiously and easily opened and set up and adjusted for use.

In addition to the advantages ascribed to my novel apparatus, it will be noted that

the apparatus is not unduly expensive, and in general is well adapted to withstand the usage to which devices of corresponding character are ordinarily subjected.

I have entered into a detailed description of the construction and relative arrangement of the parts embraced in the present and preferred embodiment of my invention in order to impart a full, clear and exact understanding of the said embodiment. I do not desire, however, to be understood as limiting my self to the precise construction and arrangement disclosed, my invention being defined by my appended claims within the scope of which modifications in structure and in arrangement may be made without departure from my invention.

Having described my invention, what I claim and desire to secure by Letters Patent, is:

1. A game apparatus comprising an apertured board, wings of netting at opposite sides of said board, a supplemental guard of netting above the board, and means associated with the board for maintaining the same in upright position; the said wings being provided with marginal cables, and the said cables being equipped at their lower ends with weights adapted to maintain the netting of the wings in distended state.

2. A game apparatus comprising an apertured board, top members hingedly connected with said board, a pocket carried by the board and said top members and disposed in rear of the board and having a bottom wall declined at a point in coincidence with the lower aperture of the board, and guard means above and at opposite sides of the board; the said pocket being formed in part by side walls and a bottom wall of flexible material, and the guard means at the side of the board being formed of sections of netting with marginal cables and weights, and the guard means above the board being formed by extension rods adjustably connected to the top members and netting carried by and interposed between said rod extensions.

3. A game apparatus comprising an apertured board, extension means adjustably connected with said board, guard means disposed above the board and carried by said extension means, and side wings of netting associated with the board and provided on their outer portions with weights for maintaining them in distended state.

4. An apparatus for use in the practice or playing of the game of golf, comprising an apertured board or wall, and guard netting and extension means and weights for holding said all in useful position.

In testimony whereof I affix my signature.

JERRY T. DWYER.
